UNITED STATES PATENT OFFICE.

AUGUSTIN LEON JEAN QUENEAU, OF PHILADELPHIA, PENNSYLVANIA, ASSIGNOR TO QUENEAU ELECTRIC ZINC FURNACE COMPANY, OF PHILADELPHIA, PENNSYLVANIA, A CORPORATION OF DELAWARE.

METALLURGY OF ZINC.

1,006,877.

Specification of Letters Patent. Patented Oct. 24, 1911.

Application filed June 8, 1911. Serial No. 631,952.

To all whom it may concern:

Be it known that I, AUGUSTIN L. J. QUENEAU, a citizen of the Republic of France, and resident of 929 Chestnut street, 5 city of Philadelphia, county of Philadelphia, State of Pennsylvania, have invented certain new and useful Improvements in Metallurgy of Zinc; and I do hereby declare the following to be a full, clear, and 10 exact description of the invention, such as will enable others skilled in the art to which it appertains to make and use the same.

In a certain prior application for Letters Patent of the United States, Serial Number 15 536,791, filed January 7, 1910, I have shown and described a method and apparatus for the extraction of zinc from zinc ores and similar reducible compounds of zinc, by the expedient of supplying the charge to be reduced 20 into a rotary reducing chamber and upon a molten resistor contained therein, which resistor is maintained, during the reducing operation, at a sufficiently high temperature, by the passage of a suitable electric current, to effect the reduction of the zinc ore or compound and the volatilization 25 of the zinc, which is thereupon recovered in a suitable condenser.

The present invention relates to improvements upon what is described and shown in my former application for Letters Patent referred to.

Particularly, it consists in a simplification of the furnace structure in some respects, and in certain improvements in effecting the condensation of the zinc vapors.

In the drawings, Figure 1 represents, in longitudinal section, an apparatus embodying my present improvements. Fig. 2 represents a vertical cross-section thereof taken on a plane indicated by the line 2, 2 of Fig. 1. Fig. 3 represents a vertical cross-section through the condenser taken on a plane indicated by the line 3, 3 of Fig. 1. Fig. 4 indicates the end view, partly in section and on a larger scale.

Similar letters of reference indicate similar parts throughout the several views.

As in my former application, the reducing chamber is of the rotary type, that is, it is a chamber adapted to be rotated continuously or intermittently in one direction,

or alternately in opposite directions, so as to subject the contents of the chamber to a tumbling action. It is provided with a 55 molten resistor D, which may be of molten metal (such as iron containing phosphorus, in the preferred proportion of 12%, by weight, so as to impart to it high resistance), or of molten slag, which I prefer in 60 practice, and which may consist of a slag left over from a former operation in the chamber, or that may be supplied from any suitable source. When slag is used as a resistor, it should be highly fluid, and, in 65 making up the charge of ore to be reduced, care is to be taken that it shall also be so compounded as to produce a highly fluid slag, to which end, if need be, some additional slag-forming ingredient may be added, 70 as, for instance, fluor spar, or phosphoretic slag from an open hearth steel furnace or the like.

The reducing chamber is provided with an outer metallic shell h (preferably of low 75 carbon steel), which may be provided with tire rings d secured thereto, which rings rest upon flanged rollers e, the axis of the chamber being usually horizontal. The shell is further provided with a band gear f, which 80 constitutes an element of a variable drive, adapted to be actuated from a variable speed motor, so that the number of revolutions or oscillations of the chamber may be readily varied. The rotary chamber is provided 85 at one end with a metallic plate h, having a hub projection x which, in turn, is adapted to be closed by an end-plate E. Near the outer edge of the plate h is a series of apertures through which pass a corresponding 90 series of bolts i. These bolts likewise pass through a stationary flange j of the shell and through the slideable ring l. They are provided with screw-threads at their ends and with adjusting nuts and 95 washers, as shown. Springs m are interposed between the flange j and ring l and encompass the bolts, so that the plates h may have a capacity for independent movement, to correspond to the effects of heat 100 expansion, but will, nevertheless, be held in strong elastic adjustable contact with the end of the chamber. The bolts are held out of electrical contact with the plate h, the

flange *j* and the ring *l* through which they pass, by means of insulating sleeves, as shown, and the springs *m* rest against insulating washers and are out of electrical contact with the flange *j* and the ring *l*, so that no electric current shall pass through the springs, to affect their temper or resiliency. The end-plate *h* is provided with a flange *v*, or its equivalent, adapted to make contact with one of the lead brushes *y* of the external circuit, as shown.

The opposite end of the rotary chamber is closed by a plate *h'*, and is connected to the shell *k* by means of the same instrumentalities that are used for connecting the plate *h* to the shell. The plate *h'*, however, is intended to be, at all times, electrically connected to the shell *k*, and this is effected through the instrumentality of a series of 20 spring metal plates *G* connecting the plate *h'* with a flange on the shell *k*, as shown. The plate *h'* is accordingly held in strong electrical adjustable contact with the end of the chamber, regardless of the effects of heat 25 expansion. The plate *h'* may be conveniently provided with suitable recesses *M* adapted to be cooled by air or water, as the case may be. The other lead *z* from the external circuit (when a direct or a single-phase alternating current is employed) may contact with the shell *k* through the intermediary of the tire ring *d*, as shown.

The shell *k* is provided with an outer lining *a* of fire brick, (preferably silica brick) 35 and an inner lining of magnesite brick, chrome brick, or the like, resistant or neutral to the slag employed or produced in the furnace chamber. The end courses *C* are made of a conducting mixture of graphite, 40 dead-burned magnesia, and tar or other carbonaceous binder, in brick or block form, the bricks or blocks having first been suitably baked at a sufficiently high heat to drive off their volatile constituents and to convert 45 them into conductors of the first order. Exterior to the courses *C* are the graphite end linings *n*, adjacent to the end-plates *h*, *h'*. With this arrangement, the circuit is completed from the lead *y* to the plate *h*, thence 50 by the adjacent graphite end lining *n* and the conducting courses *C*, to the fluid conductor *D*, thence to the conducting courses *C* at the other end of the chamber, the graphite end lining *n* at said end, the plate *h'*, and the bow-spring conductors *G*, the shell *k*, and the ring *d*, to the opposite lead *z* of the circuit.

At its middle portion, the inner lining of the furnace is preferably somewhat wider, 60 so as to form a well, of greater or less depth, *E'*, for the more convenient assembling of the heavier metals that may be present in the charge. The tubular hub projection *x* is provided with a magnesite brick or 65 chromite brick lining, which is continued

beyond the plate *h*, thereby likewise forming a portion of the end lining of the chamber, and providing a channel through which the charge of zinc ore and reducing material is supplied to the interior.

70

F indicates a plug for confining the charge and excluding air.

At the opposite or condenser end of the chamber are provided the magnesite or chromite brick courses *a²*, *b²*, which flare 75 outwardly into the condenser.

75

The condenser, in the form shown in the drawings, consists of a shell *k'*, having at one end an annular angle flange *N*, whereby it is bolted to the end-plate *h*. At its opposite end, the shell *k'* is supported from the same plate *h'* by means of screw-threaded rods *f'*, provided with turnbuckles *k²*, for adjusting their tension.

80

At the end proximate to the course *a²* the condenser is provided with a course *c²* of magnesite brick or chrome brick, likewise flaring in the same general direction as the courses *a²*, *b²*, and spaced at suitable intervals along the length of the interior of the 90 condenser are arranged the baffle dip partitions *L*, which may conveniently be made up in sections, as indicated in Fig. 3, so as to be the more readily removable and insertible. These partitions are provided with a 95 series of apertures *o*, as shown, and also with a central aperture *p*, the latter being provided so as to afford access to the exit-opening *s* from the reducing chamber, in case that opening should become clogged. The 100 partitions *L* are held in place by intermediate courses *c'* of slightly lesser internal diameter, and the extreme outer end of the condenser chamber is conveniently lined with a refractory lining *A*. The combustible gases, such as carbon monoxid, escape 105 from the condenser through the prolong *B* together with any zinc vapors that may possibly have escaped condensation, and if so desired, the prolong may communicate with any suitable receptacle for the recovery of 110 such vapors in the form of zinc oxid or of blue-powder. Finally, the condenser is provided with means for regulating its temperature, consisting of a pipe *P* having a 115 refractory outer lining *d³*, if necessary, and a hollow interior into which enters a pipe *o³*, which is supplied either with cold water or air, or hot water or air, as the case may be, through the supply pipe *b³*. By this expedient, the temperature prevailing within the condenser may be carefully regulated, 120 the cooling or heating fluid passing out through the exit pipe *a³*. The condenser is provided with a suitable tapping aperture 125 *s'*, and the reducing chamber itself is provided with a tapping aperture closed by the metallic plug *e'* and the removable refractory plug *C'*.

115

120

125

In the practice of the invention, before 125

admitting the zinc ore charge, the furnace is heated preliminarily. This heating may be effected, if desired, by a gas or oil flame, or by admitting into the furnace a body of 5 molten lead or other metal of low melting point, and passing the electric current through the furnace while subjecting it to a slow movement of rotation. When the furnace lining has attained the necessary 10 temperature, the furnace is stopped and the lead or other like material is tapped off. A known amount of resistor, preferably melted before it is inserted in the furnace, is then introduced, sufficient to reach the level 15 desired, and the charge of mixed zinc ore and coke or other reducing agent is fed in.

The charge may consist of a mixture of zinc ore and coke, wherein the coke is but slightly in excess of that theoretically required for the reduction of the ore. This 20 mixture is preferably preheated to as high a temperature as the coke will tolerate without ignition (say, to a temperature of about 500° C.), by placing it in a rotary furnace 25 of the muffled type, heated exteriorly by the products of combustion from any suitable heating furnace. The rotary furnace referred to contains a suitable number of steel balls and therefore serves as a ball mill. The 30 rotation of the ore and coke mixture during the heating and grinding operation in the ball mill furnace serves to insure the highest possible homogeneity of the mixture and the uniform heating of the individual particles. The charge is then transferred to the 35 reducing chamber and deposited upon the fluid resistor therein, whereupon the reducing chamber is then closed and slowly rotated, the electric current maintains the necessary thermal conditions for the reduction 40 of the ore and the volatilization of the zinc.

The gaseous and volatile products of the reducing operation enter the condenser, wherein is already located a relatively large 45 body I of molten zinc, which has been previously introduced therein. As the condenser slowly revolves, with the reducing chamber, (say about 1 revolution in from 8 to 10 minutes) the upper and hotter parts 50 of the partitions L pass through the molten zinc and are cooled thereby, this cooling being facilitated by the presence of the openings which increase proportionately the cooling and condensing surfaces. Furthermore, 55 the frictional contact of the partitions with the vapors, and any zinc that may adhere to the partitions, facilitate the condensing effect. To these factors, and to the large surface contact of the zinc vapors with the 60 molten zinc in the bottom of the condenser and the baffling effect of the partitions, likewise contributes the careful regulation of the temperature of the condenser, all combining to bring about an effective condensa- 65 tion of the zinc vapors in the form of metal-

lic zinc, which joins the main body of zinc I in the condenser. When a sufficient quantity of zinc has accumulated, the rotation of the apparatus is temporarily interrupted and the requisite amount is tapped from the 70 openings 8, leaving a remaining body sufficient to carry on the operation when the rotation of the apparatus is resumed.

The lining of the condenser as well as the material of the partitions L may conveniently consist of Dixon graphite, compounded with clay, so as to make substantially the same material that is employed for the ordinary graphite crucible. This material is preferred because it is tough, 80 smooth, easy to clean, resistant to shocks without breaking, and for the further reason that it keeps the metal "sweet." The condenser has the advantage of relatively large volume, large cross-section, and large 85 contact surface to the passing vapors, as well as large contact surface of zinc for said vapors, and, inasmuch as it is provided with means for carefully regulating the temperature, all of the conditions are present for 90 obtaining a satisfactory condensation of the zinc, while permitting the free escape of the carbon monoxide and other like gases. In fact, it will, of course, be evident that the condenser may be employed generally in 95 connection with reducing chambers for the treatment of zinc ores and compounds, other than the reducing chamber herein shown and described.

Having thus described my invention what 100 I claim is:

1. An electric furnace for the metallurgy of zinc ores and compounds, comprising a reducing chamber, a fluid resistor therein, and means for heating said fluid resistor 105 electrically, the electric current being introduced into the fluid resistor and taking its exit therefrom through the intermediacy of a portion of the furnace lining consisting of a mixture of refractory material and carbonaceous material constituting an electrical 110 conducting body of the first order; substantially as described.

2. An electric furnace having a reducing chamber provided with a longitudinally-expansible lining, in combination with a conducting end plate held in yielding relationship thereto through the intermediacy of an interposed refractory conductor; substantially as described.

3. An electric furnace having a reducing chamber provided with a longitudinally-expansible lining, in combination with a conducting end-plate held in yielding relationship thereto through the intermediacy of an 125 interposed refractory conductor, said conductor consisting in part of an annular course of refractory conducting blocks extending within the furnace interior, and in part of an outer annular course of refrac- 130

tory conducting blocks intermediate thereof and the conducting end-plate; substantially as described.

4. An electric furnace having a reducing chamber, provided with a longitudinally-expansible lining, and with yielding conducting end plates, a fluid resistor within the chamber, and refractory conductors in electric connection with the end plates and 10 bridged by the fluid resistor; substantially as described.

5. An electric furnace for the metallurgy of zinc ores and compounds, comprising a rotatable reducing chamber, a fluid resistor 15 therein, means for heating said fluid resistor electrically and a condenser communicating with the interior of the rotatable reducing chamber by means of a flaring opening, thereby quickly expanding the vapors 20 as they enter the condenser; substantially as described.

6. An electric furnace for the metallurgy of zinc ores and compounds, comprising a rotatable reducing chamber, a fluid resistor 25 therein, means for heating said fluid resistor electrically, and a condenser rotating with the reducing chamber, said condenser being provided with transverse partitions, which, as the condenser rotates, pass through the 30 zinc in the bottom of the condenser and are cooled thereby; substantially as described.

7. An electric furnace for the metallurgy of zinc ores and compounds, comprising a rotatable reducing chamber, a fluid resistor 35 therein, means for heating said fluid resistor electrically, and a condenser rotating with the reducing chamber, said condenser being provided with transverse partitions, said 40 partitions having openings therein, which,

as the condenser rotates, pass through the zinc in the bottom of the condenser and are cooled thereby; substantially as described.

8. An electric furnace for the metallurgy of zinc ores and compounds, comprising a rotatable reducing chamber, a fluid resistor 45 therein, means for heating said fluid resistor electrically, and a condenser rotating with the reducing chamber and provided with means for regulating the temperature prevailing in the condenser, said means consisting of a tempering pipe entering the condenser and supplied with a tempering fluid; 50 substantially as described.

9. An electric furnace for the metallurgy of zinc ores and compounds, comprising a 55 rotatable reducing chamber, a fluid resistor therein, means for heating said fluid resistor electrically, a condenser rotating with the reducing chamber and provided with transverse baffling partitions, and a tempering 60 pipe entering the condenser axially and supplied with a tempering fluid; substantially as described.

10. An electric furnace for the metallurgy of zinc ores and compounds, comprising a 65 rotatable reducing chamber, a fluid resistor therein, means for heating said fluid resistor electrically, a condenser a series of perforated disk partitions spaced apart in said condenser, and a tempering pipe entering 70 said condenser axially and supplied with a tempering fluid; substantially as described.

In testimony whereof I affix my signature, in presence of two witnesses.

AUGUSTIN LEON JEAN QUENEAU.
